US0D1077892S

(12) **United States Design Patent** (10) **Patent No.:** **US D1,077,892 S**
(45) **Date of Patent:** **** Jun. 3, 2025**

(54) **PROJECTOR**

(71) Applicant: **Hongqing Zhang**, Zhumadian (CN)

(72) Inventor: **Hongqing Zhang**, Zhumadian (CN)

(**) Term: **15 Years**

(21) Appl. No.: **29/964,239**

(22) Filed: **Sep. 22, 2024**

(51) **LOC (15) Cl.** **16-02**

(52) **U.S. Cl.**

USPC **D16/230**

(58) **Field of Classification Search**

USPC D16/221, 225, 230, 231, 234; D21/514

CPC G03B 21/16; G03B 21/145; G03B 21/32;

G03B 21/14; G03B 21/00; G03B 21/001;

(57) **CLAIM**

The ornamental design for a projector as shown and described.

DESCRIPTION

FIG. 1 is a perspective view of a projector showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the projector that form no part of the claimed design.

1 Claim, 8 Drawing Sheets
